Patented Sept. 2, 1924.

UNITED STATES PATENT OFFICE.

FRED F. JONES, OF CHILLICOTHE, OHIO.

FOUNTAIN CUSPIDOR.

Application filed November 5, 1923. Serial No. 673,013.

To all whom it may concern:

Be it known that I, FRED F. JONES, a citizen of the United States, residing at Chillicothe, in the county of Ross and State of Ohio, have invented certain new and useful Improvements in Fountain Cuspidors, of which the following is a full, clear, and exact description.

My invention relates to cuspidors of the fountain type such as are used in connection with dental chairs, and has for its object to modify the cuspidor now in common use so that refuse material such as cotton waste, extracted teeth, paper cups and the like may be deposited in the bowl thereof without danger of clogging the drain pipe. To this end I have provided a receptacle of substantial diameter in which is located a wire mesh receptacle for receiving the waste material.

One of the advantages of the present invention resides in the provision of a cuspidor in which the dentist may deposit all refuse matter resulting from his dental operation without leaving his position adjacent to the chair.

Other objects and advantages of the invention will be apparent from the following description when taken in connection with the accompanying drawings, in which—

Figure 1 is a side elevation, partly broken away, of one form of the invention.

Figure 2 is a side elevation of a slightly modified form, and,

Figure 3 is a side elevation of a still further modified construction.

Referring to the drawings more in detail, the numeral 1 indicates the usual bracket by which fountain cuspidors are attached to dental chairs. Such a cuspidor is referred to by the numeral 2 and the flush pipe and attachments by the numeral 3.

In such apparatus a copper wire screen is set in the discharge port of the cuspidor to prevent waste material inadvertently deposited therein, from clogging the waste pipe. The waste material is caught by the wire screen and presents an unsightly appearance both to the dentist and patient.

In the present invention the wire screen is removed and a receptacle 4 of rather large diameter is connected to the discharge port of the cuspidor. Interposed between the receptacle 4 and the discharge port 5 of the cuspidor is what may be termed a closure 6. This closure is provided with a spout 7

which is received within the clamp ring 8 of the bracket 1. The closure 6 and receptacle 4 are hingedly connected as indicated at 9, while a latch 10 is provided for holding the apparatus closed.

Mounted within the receptacle 4 is an inner waste receptacle 11. This receptacle is formed of foraminous material and is provided with reinforcing members 12 which extend somewhat below the bottom thereof to provide legs 13 which space the same from the bottom of the outer receptacle 4. By this construction it will be seen that waste material may be thrown into the cuspidor at will, and will immediately disappear into the waste receptacle without in any way interfering with the flow of water. At the close of the day the latch 10 may be released and the receptacle 4 swung to the dotted line position, thereby permitting withdrawal of the waste receptacle 11 for emptying.

The modified form of the invention shown in Figure 2 is identical with that previously described except in the connecting means between the receptacle and closure. In the modified form the closure 20 is provided with a flange 21 and the receptacle 22 with a flange 23. These flanges are pivotally connected as indicated at 24, and a locking bolt 25 secures the receptacle in closed position. In this form of the invention the waste receptacle may be removed and emptied by swinging the receptacle 22 on its pivot 24 through about 180° in a horizontal plane. In both forms of the invention a drain pipe 26 is provided for drawing off the water. A pedestal form of the invention is shown in Figure 3 of the drawings and comprises a hollow pedestal 30 in which are housed the waste pipe 31 and the feed pipe 32; a door 33 being provided to give access thereto. The foraminous waste receptacle 34 is situated in the upper end of the pedestal and in order that the same may be removed for emptying, the closure 35 with which the cuspidor is connected is pivotally attached to the upper end of the pedestal. This construction, of course, necessitates a ball and socket connection 36 between the two sections of the feed pipe at the pivot point. In this form of the invention the waste receptacle may be removed by releasing the latch 37 and swinging the bowl 2 and cover 35 to one side.

From the foregoing description taken in connection with the accompanying drawings it will be seen that I have provided an exceedingly simple construction whereby the 5 usual fountain cuspidor may serve to a large extent as a waste receptacle without in any way clogging the same; also that convenient means are provided by which the same may be relieved from time to time 10 of the waste material collected.

In accordance with the patent statutes, I have described what I now believe to be the best embodiment of the invention, but I do not wish to be understood thereby as limiting myself or the scope of the invention, as 15 many changes and modifications may be made without departing from the spirit of the invention; all such I aim to include in the scope of the appended claims.

20 What I claim as new and desire to secure by Letters Patent is:

1. In a device of the class described a fountain cuspidor, a receptacle below said cuspidor, a pivotal connection between said 25 receptacle and cuspidor, and a foraminous receptacle positioned within said first-mentioned receptacle.

2. The combination with a fountain cuspidor, of a receptacle and closure, said 30 closure being provided with an opening registering with the discharge port of the cuspidor, a foraminous waste receptacle positioned within said first-mentioned receptacle, and means connecting the first- 35 mentioned receptacle and closure whereby

the former may be moved to a position to permit the removal of the foraminous waste receptacle.

3. The combination with a fountain cuspidor, of a receptacle and closure, said 40 closure being provided with an opening registering with the discharge port of the cuspidor, a foraminous waste receptacle positioned within said first-mentioned receptacle, spacing means interposed between 45 the bottoms of said receptacles, and means connecting the first-mentioned receptacle and closure whereby the former may be moved to a position to permit the removal of the foraminous waste receptacle. 50

4. The combination with a fountain cuspidor, of a receptacle and closure said closure being provided with an opening registering with the discharge port of the cuspidor, a pivotal connection between said 55 closure and receptacle, and a foraminous waste receptacle positioned within said first-mentioned receptacle.

5. The combination with a fountain cuspidor, of a receptacle and closure said 60 closure being provided with an opening registering with the discharge port of the cuspidor, a pivotal connection between said closure and receptacle, a foraminous waste receptacle positioned within said first- 65 mentioned receptacle, spacing means between the bottoms of said receptacles, and a discharge conduit leading from the bottom of the first-mentioned receptacle.

FRED F. JONES.
